TAPE EMBOSsing TOOL

Charles R. Rhodes, Pleasant Hill, Calif., assignor to Dymo
Industries, Inc., Emeryville, Calif., a corporation of
California

Filed Aug. 26, 1969, Ser. No. 18,855

Term of patent 14 years

Int. Cl. D18—99

U.S. Cl. D64—10

FIG. 1 is a perspective view of a tape embossing tool showing the new design.

FIG. 2 is an end elevational view thereof as seen from the left of FIG. 1;

FIG. 3 is an end elevational view as seen from the right of FIG. 1;

FIG. 4 is a top plan view thereof; and

FIG. 5 is a side elevational view thereof.

The undisclosed side presents a substantially similar appearance as that of FIG. 5.

I claim:

The ornamental design for a tape embossing tool, substantially as shown and described.
